JAMES H. BEVINGTON, OF CLEVELAND, OHIO, ASSIGNOR TO THE
CRESCENT APPLIANCE CO., OF BEREAL, OHIO, A CORPORATION
OF NEW JERSEY.

REPEATING TORPEDO-CANE.

No. 840,425.

Specification of Letters Patent.

Patented Jan. 1, 1907.

Application filed August 1, 1903. Serial No. 167,850.

To all whom it may concern:

Be it known that I, JAMES H. BEVINGTON, a citizen of the United States, residing at Cleveland, in the county of Cuyahoga and State of Ohio, have invented certain new and useful Improvements in Repeating Torpedo-Canes; and I do declare that the following is a full, clear, and exact description of the invention, which will enable others skilled in the art to which it appertains to make and use the same.

My invention relates to a repeating torpedo-cane; and the invention consists in the construction of cane substantially as shown and described, and particularly pointed out in the claims.

In the accompanying drawings, Figure 1 is a perspective elevation of one form of my improved cane; and Fig. 2 is a longitudinal sectional elevation thereof on a line corresponding to $x-x$, Figs. 3 and 4, and enlarged as compared with Fig. 1. Fig. 3 is a plain elevation of the cane with the torpedo-magazine at the front, and Fig. 4 is a plan view 25 looking down on Fig. 3 from line $y-y$ thereon. Fig. 5 is an elevation of a modification of the invention. Fig. 6 is a perspective view of the device for releasing the torpedoes shown in Figs. 1 and 3.

30 A represents a cane or staff, preferably of wood for lightness and convenience in handling, but which may be of metal and tubular, if preferred, and H is a metallic head in which the cane or cane-handle is shown as socketed. 35 The said head has an internal explosion-chamber c and which has a flat or equivalently-shaped upper surface 2, serving as an "anvil," so-called, or striking-surface for plunger B. The said plunger has the usual 40 stem extending down beneath head H and a confining and striking head 3 of its own in chamber c also, as is now common in torpedo-canes.

45 Explosion-chamber c has an exhaust or discharge 4 at one side, as shown in this instance, and a receiving inlet or mouth 6 on the opposite side; but I may make said head with a single opening for both receiving the torpedo and discharging the explosion. The 50 mouth 6 is also shown as standing out and flaring sufficiently to intercept the torpedo as it drops from the magazine-chute and direct it into the explosion-chamber, even if the cane be more or less inclined at the time.

The torpedoes are adapted to be automatically released or dropped from their magazine or chamber C with each downward stroke of the cane and consequent explosion of a torpedo, and which makes room for another torpedo when the plunger B drops down, and so on successively until an entire charge of torpedoes is exhausted.

The magazine or chamber C may be more or less formed or developed in the cane itself or an added part. In this instance it is shown as added against a flattened surface 8 of the cane and is formed of sheet metal struck up with a channel lengthwise corresponding substantially to the size of a torpedo and fastened along its edge to handle A by means of short tacks or pins 7 or otherwise.

The torpedoes provided for herein are preferably of disk shape, rather than spherical, and are introduced to the magazine through an opening 9 in its top.

Suitable trip or releasing mechanism for the torpedo is provided, and this may be largely varied in construction and operation and serve my purpose, so that I do not regard myself as limited to the particular mechanism shown. However, as shown herein, I employ a combined stop and releaser S, referred to also as a trigger and preferably made of a piece of flat metal pivoted at 10 and having two separated fingers 11 and 12 bent back beneath itself and reaching a short distance into the magazine for the torpedoes and serving alternately as means to stopping and releasing the torpedoes. The 15 opposite end of trigger S is directly or indirectly engaged by a retracting-spring 14, which may be of rubber, wire, or their equivalent; but rubber is preferred, because it is easily replaced, and which holds trigger S normally closed under the pile of torpedoes, as herein shown. A wire or connection R unites plunger B operatively with the trigger S and actuates the trigger each time said plunger is struck to produce an explosion.

This downward stroke of the cane and upward stroke of the plunger throws the upper or stop finger 11 outward from under the pile of torpedoes and the longer lower finger inward, and the net effect of this is to feed the lowest torpedo down upon lower finger 12 and suspend the others temporarily, the said lower finger being longer than the upper

one, as shown. Then as the cane is raised and plunger B drops both by gravity and the action of spring 14 trigger S is instantly reversed, and its shorter finger 11 gets back 5 under the pile of torpedoes and holds them up while longer finger 12 moves out from beneath the torpedo it held in check, and said torpedo instantly drops into the explosion-chamber.

10 It will be noticed as a material feature in this cane that there is a comparatively deep open space between extremity 15 of the chute of the magazine below trigger S and the mouth 6 of head H, which receives the 15 torpedo, and it is also seen that said chute is more or less open its full length at its front. This wholly overcomes the danger of ignition of the torpedoes in the magazine by possible back-firing through mouth or receiving opening 6 when an explosion occurs, even if this be the only opening in the head H, and must serve also for its discharge. Obviously this is a danger to be carefully guarded against, and I have wholly overcome the danger by 20 keeping the magazine of torpedoes removed a distance from the explosion-chamber, and in any event having a wide space open to the outer air and outside the explosion-chamber between said chamber and the nearest torpedo. Hence any discharge into space after this manner comes as a mere puff, which instantly dies, and danger is avoided. If there were any tendency for the explosion to work upward, it would be dissipated in the 25 open chute beneath trigger S; but I do not find any real danger in this direction.

Fig. 5 illustrates a modification of the invention, wherein the trigger S is manipulated through a rod V, extending from the trigger 40 to the top of the cane and having a hoop or loop 18 or some equivalent construction for raising said rod and actuating the trigger whenever a torpedo is to be released.

Another feature of my invention is the position-determining handle 20 for using the 45 cane and which is shown as projecting in a plane parallel to opening 6 for receiving the torpedo to the explosion-chamber. Then as the said handle is carried in the right hand 50 with the stem extending back toward the wrist in a natural way the exhaust or outlet 4 is thrown outward away from the person, and the danger of discharging against one's leg is averted. I may make the canes rights 55 and lefts in this particular, if desired.

The chute portion of magazine C is that portion below trigger or releasing device S and in a full-sized cane is removed at least six inches above the mouth 6. Any suitable 60 chute or conduit for the torpedoes from this point downward may be used.

What I claim is—

1. A repeating torpedo-cane provided with a magazine for torpedoes, and a head on said

cane having an explosion-chamber, itself 65 having a firing-anvil, and the opening to said chamber to introduce the torpedoes being on the outside of the head and separated from the chute of the magazine by an outer open air-space, thereby preventing possible ignition of the torpedoes in the magazine, and a plunger working in the head and adapted to admit the explosives into the head when it recedes from the firing-anvil.

2. A repeating torpedo-cane having a head 70 with an explosion-chamber and a receiving opening thereto on its outside and exposed to the outer air, and a magazine for torpedoes open at its bottom to the outer air and spaced apart from said receiving-opening, and release mechanism for the torpedoes, substantially as described.

3. A repeating torpedo-cane having a magazine for torpedoes, and a pivoted releasing device having a pair of fingers reaching into 85 said magazine on different planes one above the other, substantially as described.

4. A repeating torpedo-cane having a magazine on its outside and an explosion-chamber with a mouth to receive torpedoes directly 90 beneath said magazine and separated therefrom by an air-space outside of the cane, a releasing device for the torpedoes, and means to actuate the same, and means to restore said device to closing position, substantially 95 as described.

5. A torpedo-cane having a head with an explosion-chamber and a mouth open thereto on the outside of the head, a magazine having its outlet on the outside of the cane 100 and wholly separated from said head and with an open outer air-space between the same and the said mouth, in combination with a releasing device adapted to intercept the torpedoes and release one at a time, said 105 device located at the upper end of the chute portion of said magazine, substantially as described.

6. A repeating torpedo-cane comprising a magazine for torpedoes, and a head having 110 an explosion-chamber containing a firing place or anvil and having an entrance-opening located on the outside of the chamber and into which the torpedoes are introduced, and separated from the chute or lower end of said 115 magazine by an outer open space, thereby preventing possible ignition of the torpedoes in the magazine, and a firing plug or plunger admitting an explosive into the explosion-chamber when it moves from the firing place 120 or anvil.

In testimony whereof I sign this specification in the presence of two witnesses.

JAMES H. BEVINGTON.
